Primary Examiner—Catherine R. Oliver

(57) **CLAIM**

The ornamental design for an insect bait station, as shown and described.

DESCRIPTION

FIG. 1 is a perspective view of an insect bait station showing our new design;

FIG. 2 is a top plan view thereof;

FIG. 3 is a front elevational view thereof with the rear elevational view being identical thereto;

FIG. 4 is a right side elevational view thereof with the left side elevational view being identical thereto; and,

FIG. 5 is a bottom plan view thereof.

The broken lines in FIGS. 1, 3, 4 and 5 are for illustrative purposes only and forms no part of the claimed design.
